SUPPORT FOR ELECTRICALLY HEATED
SADIRONS

Helene A. Schack, St. Paul, Minn.

Application March 8, 1939, Serial No. 260,551

3 Claims. (Cl. 248—117.2)

My invention relates to a new appliance that affords a safe, convenient and inexpensive support for an electrically heated sadiron and its cooperating electric conductor cord.

5 My invention furthermore relates to an electric sadiron support whose supporting platform is provided with cross ventilating means permitting air to be drawn up through the platform, and,

10 It is a further object of my invention to provide a mounting that rigidly holds the sadiron supporting appliances upon an edge of an ironing board so that the sadiron supporting tray is on a plane above the plane of the ironing board and likewise to the rear of the same, and,

15 It is a further object of my invention to provide a complete peripheral raised edge as a guard to prevent the sadiron being moved from the supporting means without lifting, and,

The further objects of my invention that are 20 new and novel will be more fully presented in the following specification, to this end, in the drawing,

Figure 1 is a perspective view of my invention showing the ventilated base of the supported sad- 25 iron tray and its cooperating cord sustaining member, the upper part of which is broken away.

Figure 2 is a top view of my invention showing the transverse and longitudinal ventilating means attained by the said sadiron supporting lips ex- 30 tending up from the base of the tray.

Figure 3 is an end view of my invention showing the clamping means, the cord holder with its fastening means and the cord suspending loop atop the cord holder.

35 Figure 4 is a cross section of the tray, taken on the line 4—4 of Figure 2, through the sadiron tray, showing the sadiron supporting lips, the ventilating slots, and the peripheral raised edge guard.

40 Figure 5 is a front view of my invention clamped to an ironing board with the upper part of the cord holder broken away.

Figure 6 is a perspective view from the rear of the cord holder sustaining mounting, showing in 45 detail its supporting and locking means as applied to the general construction of my invention.

Figure 7 is an enlarged perspective view of a 50 corner of the electric sadiron supporting tray showing the supporting lips for the sadiron, pro- vided with projected supporting digits for the sustaining of the sadiron and thus permitting cross ventilation to the fullest possible means.

In referring to the drawing, A represents a 55 ventilated electric sadiron supporting tray of which the ventilating slots B act as air passages.

Adjacent to the slots B are upturned supporting lips C acting as the electric sadiron supports and likewise a cross reinforcement for the base of the tray. These supporting lips C are an integral part of the tray base D, being formed by the up- bending of the metal from the slot B and thereby affording not alone the raised sadiron support above the face of said tray but a structural reinforcement for the same.

The ventilated sadiron tray A is mounted at 10 its ends upon brackets E which are provided with supporting thumbs E' so as to hold the ventilated electric sadiron tray in an elevated plane parallel to the top surface of the ironing board F to which the entire unit is made fast for op- 15 eration.

The supporting brackets E are further provided with jaws E² and supporting bracket struts E³. The bracket jaws E² are provided at their holding ends with an enlarged knob end E⁴ through 20 which is threaded a thumb screw 2, sustaining contact wobble heads 2a upon their upper terminations as locking elements for the said clamp brackets E.

The supporting brackets E are further provided at their rearward termination 3 with a flat downward projecting stop lip 4 and a tray paralleling cord rod sustaining member 5 the latter of which carries the cord rod socket member 6 held piv- 25 otally in rotatable position by a pivotal holding means 7 onto sustaining member 5.

The cord socket member 6 which is originally a cross shape is provided with a squared socket 8 being formed by bending the lip 6a into a squared socket as shown, while the lip 6b to opposite side of said socket member is provided with inwardly bent travel locking means 9 and 10 re- 30 spectively. The upper locking wing 9 when placed to the rear of the right hand bracket, for a right handed person will arrest a greater angled turn than the perpendicularizing of the cord rod socket 8 while the lower locking wing 10 when rotated about the pivotal point 7 abuts onto the stop lip 4 and arrest any greater angled turn than the horizontalizing of the cord rod socket 8.

The squared socket 8 is the receiving member of the squared terminating end 11 of the cord suspender 12 which is provided at its head with a spiraled loop 13 slidably sustaining the electric cord well above the hand line of the sadiron and handle thereof resting upon the ventilated sadiron tray A. The entire periphery of the venti- 40 lated sadiron tray A is further provided with an upward extending guard 14 to arrest any removal 45 of the electric sadiron from the tray other than 50 55

by lifting the same from within the lipped guard.

The upper faces of the sadiron supporting lips C extending upwards from the tray face D and 5 providing ventilating means B through the base of the tray, are provided with depressions 20 in the supporting lip faces. These depressions 20 allow little supporting surfaces 21 of the supporting lips C to act as the actual rest for the 10 electric sadiron.

In operation, assuming that the party utilizing this invention to be a right handed person, the sadiron tray unit with brackets would be first made fast upon the ironing board's end edge, the 15 jaws of the clamps straddling the said board and its accompanying padding and cover. The clamping means of the brackets afford rigid suspension by means of thumb screws fastenings, so that the tray will be sustained in an elevated 20 line parallel to the top surface of the ironing board and to the rear of the same.

The cord sustaining mounting would then be pivotally attached to the rear right hand corner of the tray support as is best shown in Figure 6 25 and made pivotally fast thereto by the pivotal support 7 sustained in proper position in lip 5. As before stated, the squared end 11 of the cord sustaining rod 12 would then be inserted into squared socket 8 and the electric cord would be 30 then threaded through the loop 13 to suspend the same at a predetermined height. The electrically heated sadiron would then be placed within the tray A to rest upon the upturned projecting digits 21 caused by the indenting of the 35 upper face of the supporting lip C. The longitudinal slots B through the base of the tray will allow a free upflowing current of air which in its expanding state would likewise flow through depression 20 thus ventilating nearly the entire base of the sadiron, and the tray absorbing only such heat as would be transmitted through the digits 21 upon which the electrically heated sadiron rests.

Should the party using this appliance be left handed the cord sustaining mounting would be reversed and used upon the rear of the left hand corner of the tray thus permitting the locking wing 9 to operate in conjunction with the left 5 hand locking lip 4 and the locking lip 10 to operate in conjunction with the underside of the tray base.

I claim:

1. An iron holder of the class described comprising a base plate formed with an upwardly projecting flange extending around its periphery, and with a series of spaced apart slots extending across said base plate, said slots being formed with upwardly extended lips and said lips being 15 formed with spaced edge indentures, whereby said lips form supports for an iron, said slots and the indentures in said lips forming air passages to bring about a transverse and longitudinal venti- 20 tilating of the bottom of a supported iron.

2. An iron holder of the class described comprising a base plate, a peripheral flange projecting upwardly from said plate, said plate being formed with transverse slots terminating short of said flange, upwardly projecting lips formed 25 by the bending of the base plate upwardly along side said slots, said lips being formed with spaced apart edge indentures, and brackets extending underneath the ends of said plate and formed at one end with jaws for securing a support, and 30 for holding said base plate in a horizontal plane spaced above such support.

3. An iron holder of the class described comprising a base plate, a peripheral flange projecting upwardly from said plate, a series of lips pro- 35 jecting upwardly from the sides of transverse slots cut in said base plate, supporting brackets for said base plate, said brackets extending along and underneath the ends of said base plate, and spaced apart jaws carried by one end of each 40 bracket to hold said base plate above the said jaws.

HELENE A. SCHACK.
